(57) **CLAIM**

The ornamental design for a speaker enclosure, substantially as shown and described where the dotted lines illustrate portions of the speaker enclosure that form no part of the claimed design.

DESCRIPTION

FIG. 1 is a perspective view of the bottom, front of the speaker enclosure in accordance with the present invention; FIG. 2 is a plan view of the left edge, thereof;

FIG. 3 is a perspective view of the top, front, thereof;

FIG. 4 is a plan view of the bottom, thereof;

FIG. 5 is a plan view of the front, thereof;

FIG. 6 is a plan view of the top, thereof;

FIG. 7 is a second perspective view of the bottom, front, thereof;

FIG. 8 is a plan view of the right edge, thereof;

FIG. 9 is a second perspective view of the top, front, thereof;

FIG. 10 is a perspective view of the top, rear, thereof;

FIG. 11 is a perspective view of the bottom, rear, thereof;

FIG. 12 is a plan view of the rear, thereof;

FIG. 13 is a second perspective view of the top, rear, thereof; and,

FIG. 14 is a second perspective view of the bottom, rear, thereof.

The broken lines in FIGS. 4, 10, 11, 12, 13, and 14 form no part of the claimed design.
